UNITED STATES PATENT OFFICE.

ROBERT FRANKLIN FIFE, OF CANTON, OHIO.

STACK-FLASHING.

1,253,884.

Specification of Letters Patent. Patented Mar. 12, 1918.

Application filed November 26, 1917. Serial No. 203,903.

To all whom it may concern:

Be it known that I, ROBERT FRANKLIN FIFE, a citizen of the United States, residing at Canton, in the county of Stark and State 5 of Ohio, have invented a new and useful Stack-Flash, of which the following is a specification.

This invention relates to stack flashings and is designed to provide a flashing that is 10 quickly and easily applied to a variety of sizes of pipe.

Another object is to provide a flashing that will readily fit roofs of various pitches with the same facility.

15 With these objects in view the invention consists in the novel construction and arrangement of parts, hereinafter described, illustrated in the accompanying drawings, and particularly pointed out in the appended 20 claims, it being understood that various changes in the form, proportions, size and minor details of construction may be made within the scope of the appended 25 claims, without departing from the spirit or sacrificing any of the advantages of the invention.

In the drawings:

Figure 1 is a sectional view of my improved flashing.

30 Fig. 2 is a similar view on a somewhat reduced scale showing my flashing applied to a pipe of comparatively small diameter.

Fig. 3 is a view similar to Fig. 2 showing pipe of slightly larger diameter than Fig. 2.

35 Fig. 4 is a cross sectional view with the calking sleeve trimmed down and a slightly larger pipe than Fig. 3 shown fitted therein.

Fig. 5 is a similar view with a still larger pipe shown in conjunction with the flashing.

40 Fig. 6 is a similar view with the flashing shown in the position it would assume on a roof of greater pitch than Figs. 2, 3, 4 and 5.

Fig. 7 is a view of a slightly modified form in which I use a plurality of grooves 45 or indentations on the calking sleeve, each groove or indentation indicating the point at which to trim the calking sleeve for different sizes of pipe.

Similar numerals of reference indicate 50 corresponding parts throughout the several figures of the drawings.

To those familiar with the installation and adjustment of flashings of this character now known and used, it is well known 55 that only a very slight variation in the sizes of pipes that can be used with a certain size

flashing, is possible. For this reason the craftsman who is to install the flashing must determine the size pipe that will be necessary for a certain job and then order his 60 flashing to fit the pipe. This necessitates either a loss of time in getting a particular size flashing for each size of pipe or the carrying in stock by the craftsman of a large 65 variety of flashings for different sizes of pipe. In order to overcome this difficulty I have designed a flashing, the calking sleeve of which has a wide range of adjustment and can fit a large variety of sizes of pipe and is also adapted to be as readily adjusted 70 to a roof of the maximum pitch as to a flat roof. As shown in the drawings my flashing comprises a sheet metal frusto-conical portion 1 which has the laterally extending flange or base 2 by means of which it is 75 secured to the roof. The upper end of this frusto-conical collar is turned outwardly to form a flange 3 about which the lower end of the calking sleeve formed of lead or similar soft malleable metal is molded. I 80 form this calking sleeve indicated at 4 of approximately twice the length of calking sleeves on flashings now known and employed and about mid-way between the upper end of the said calking sleeve and the 85 point where it is molded about the flange 3, I form a groove or indentation 5 for a purpose to be hereinafter set forth.

Referring now more particularly to Fig. 2 I have shown my improved flashing applied to a pipe of relatively small diameter such for instance as an inch and a half waste pipe and as shown in this figure, by virtue of the extreme length of the calking sleeve the craftsman is enabled to hammer it into close contact about the pipe to 90 form a water tight and air tight joint. It is readily seen that this will not be possible with a calking sleeve of the ordinary construction and of similar diameter, since the calking sleeve would neither reach to the pipe nor would it be practical even though the sleeve would just reach the pipe to hammer it sufficiently in order to do so.

Fig. 3 shows the same size of flashing 105 applied to a pipe of a slightly larger diameter than that shown in Fig. 2 and as will be readily seen in this figure, no change has been made in the flashing. Since the pipe 110 is of a slightly larger diameter a trifle less hammering is necessary to bring the calking sleeve into close contact about the pipe.

Should a larger pipe than that shown in Fig. 3 be required for the job the plumber saws around the groove 5 with a hack saw, removing the upper end of the calking sleeve, 5 which of course gives a larger diameter to the now remaining upper end of the calking sleeve and as shown in Fig. 4, the remaining portion is hammered into contact with the pipe. Should a still larger size of 10 pipe be required it is readily seen that it can be as easily used by simply hammering the calking sleeve to fit. As shown in Fig. 6 a great variation is possible in the pitch of the roofs on which this flashing can be 15 used.

Referring now to Fig. 7 of the drawings I have shown a calking sleeve with grooves 6, 7 and 8, all similar to the groove 5 and in full lines in this figure I have shown a pipe 20 of the proper diameter to fit within the extreme upper end of the said calking sleeve when a pipe of the next size larger than the one shown in full lines is to be used, the upper end of the calking sleeve is severed 25 at the groove 6 and will then take sizes of the pipe up to and including the one shown in dot and dash lines. It is thus seen that sizes of pipe up to the size indicated by lines formed with a dash and two dots can be 30 used, this being the size that would require the trimming of the calking sleeve down to the last groove.

From the foregoing it will be obvious that my flashing need only be made in a very few 35 different sizes, each size having a variation sufficient to cover a half dozen or more different sizes of pipe and since the spacing of the grooves from the upper end of the calking sleeve are designed to enable the 40 plumber to determine exactly where to trim the calking sleeve in order to leave enough metal to insure calking the pipe properly without danger of the lead cracking away from the lower portion of the flashing, a 45 considerable amount of time can be saved in applying the said flashing.

Having fully described my invention what I claim as new and desire to secure by Letters Patent, is:

50 1. A stack flashing comprising a frusto-conical collar having means for attachment to a roof and adapted to inclose a pipe, a frusto-conical calking sleeve of soft malleable material entirely surrounding and supported upon the upper end of the collar, said calking sleeve being of sufficient length to allow the upper end thereof to be forced in to accommodate several different sizes of pipe.

60 2. A stack flashing comprising a frusto-conical collar having means for attachment to a roof and adapted to inclose a pipe, an outwardly disposed annular flange provided around the upper end of said frusto-conical 65 collar, a frusto-conical calking sleeve of

soft malleable material entirely surrounding and supported upon said annular flange, said sleeve being conical on its interior and adapted to fit the pipe and be forced down thereon, said pipe being spaced from the 70 collar and from the major portion of the sleeve sufficiently to permit the collar to be set at different angles to the pipe, the sleeve being adapted to have its upper end forced into closer contact with the pipe, said sleeve 75 being of sufficient length to allow the upper end thereof to be forced in to accommodate several different sizes of pipe.

3. A stack flashing comprising a frusto-conical collar having means for attachment 80 to a roof and adapted to inclose a pipe, a frusto-conical calking sleeve of soft malleable material having a groove or indentation therein, the said groove or indentation being spaced at a predetermined point below the upper extremity of the said frusto-conical calking sleeve, the said calking sleeve being of sufficient length to allow the upper end thereof to be forced in to accommodate several different sizes of pipe, the 85 upper portion of said calking sleeve being adapted to be severed from the lower portion at the point indicated by the said groove or indentation to enable the said calking sleeve to accommodate a still larger size of 90 pipe than any hereinbefore referred to.

4. A stack flashing comprising a frusto-conical collar having means for attachment to a roof and adapted to inclose a pipe, a frusto-conical calking sleeve of soft malleable material having an annular groove or indentation therein, the said groove or indentation being spaced at a predetermined point below the upper extremity of the said frusto-conical calking sleeve, the said calking sleeve being of sufficient length to allow the upper end thereof to be forced in to accommodate several different sizes of pipe, the upper portion of said calking sleeve being adapted to be severed from the lower 100 portion at the point indicated by the said groove or indentation to enable the said calking sleeve to accommodate a still larger size of 105 pipe than any hereinbefore referred to, and the portion of the calking sleeve remaining after said upper portion has been severed at the point indicated by said groove or indentation being of sufficient length to allow the upper end thereof to be forced in to accommodate several different sizes of pipe. 110

5. A stack flashing comprising a frusto-conical collar having means for attachment to a roof and adapted to inclose a pipe, a frusto-conical calking sleeve of soft malleable material having annular grooves or indentations therein, the said grooves or indentations being spaced at predetermined points below the upper extremity of the said frusto-conical calking sleeve, the said calk- 125

ing sleeve being of sufficient length to allow the upper end to be forced in to accommodate several different sizes of pipe, the upper portions of said calking sleeve being 5 adapted to be severed from the lower portion at each of the points indicated by one of the said grooves or indentations to enable the said calking sleeve to accommodate still larger sizes of pipe and the portion of

the calking sleeve remaining after all of said upper portions have been severed down to the point indicated by the lowest of said grooves being of sufficient length to allow the upper end thereof to be forced in to accommodate several different sizes of pipe. 10 15

In testimony that I claim the above, I have hereunto subscribed my name.

ROBERT FRANKLIN FIFE.
